BED JACKET AND SIMILAR WEARING APPAREL

Toni Straus, London, England

Application September 7, 1950, Serial No. 183,484
In Great Britain August 4, 1950

3 Claims. (Cl. 2—108)

1

This invention relates to bedjackets and similar wearing apparel.

When bedjackets and similar wearing apparel of usual cut and design are to be taken off a problem is presented because the wearer has to lift up the upper part of his body and/or to turn to his side in order to be able to remove or have the garment removed.

It is in the nature of the present invention to provide a bedjacket or similar wearing apparel which avoids these disadvantages and inconveniences and which can easily be taken off by the wearer himself or be removed by a helping hand without calling for any effort on the part of, and without causing any inconvenience or trouble to the wearer. For taking off or removing the bedjacket or such like according to the present invention it is not necessary that the upper part of the body of the wearer is lifted up or turned. Even when the arms of the wearer are stiff so that they cannot be bent, the bedjacket or such like can be taken off or removed easily. This proves very convenient especially for elderly and/or ill people who should not or cannot move or be moved. Of course such a bedjacket or similar wearing apparel according to this invention is also much easier and more convenient to put on than a garment of usual cut.

This is attained by this invention by slitting the back of the bedjacket or similar wearing apparel along the centre line from the bottom edge up to near the top seam where the two parts of the garment remain permanently together. Of course, instead of slitting, the garment may be made of two separate halves which are permanently joined together for only a short length at the top part. The two parts of the divided or of two halves made bedjacket or such like are held together at the back by suitable elastic means of one kind or another which means on the one hand are strong enough to hold the two halves of the garment closely together while on the other hand these said means are elastic enough to allow for a sufficient separation of the two halves to take off or remove the garment swiftly and conveniently. In this way the bedjacket or similar wearing apparel can be taken off or removed without the wearer having to lift up or turn his body and without causing any trouble and inconvenience by simply pulling at the arms of the garment.

The accompanying drawing shows one embodiment of the present invention by way of example, and wherein:

Fig. 1 is a front elevational view of a bedjacket

of well known form with the front panels closed and showing the invention incorporated therein; and

Fig. 2 is a view similar to Fig. 1 with the front panels opened and thrown back for more clearly disclosing the invention.

As shown on the drawing the bedjacket J is of well known form and includes a back panel B, front panels F, a neck opening N and sleeves S united to the back and front panels by arm hole seams 4a and 4b. In accordance with the present invention the back panel B is centrally vertically slit at 5 from its lower edge to a point adjacent its upper edge or the neck opening N, thereby dividing the usual back panel B into a pair of panels 1a and 1b. These panels are united for a short distance from the neck opening N downwardly as indicated at 6 and these panels 1a and 1b have free overlapping edges 5a, 5b below the line of connection 6.

The free edges 5a, 5b of the respective back panels 1a, 1b, are normally maintained in lapped relation by means of two pairs of elastic strips 2a, 2b and 3a, 3b which extend transversely across the inner faces of the back panels 1a, 1b. The outer ends of these strips 2a, 3a are secured to the arm hole seam 4a and the outer ends of the strips 2b, 3b are secured to the arm hole seam 4b.

The strips 2a, 3a extend across the slit 5 and the free edge 5b of panel 1b and have their inner ends secured thereto adjacent said free edge 5b. The strips 2b, 3b extend across the slit 5 as well as the free edge 5a of panel 1a and have their inner ends secured thereto adjacent said edge 5a.

Thus it will be seen that the inner ends of the elastic strips, whose outer ends are secured to the arm hole seam, of each panel, are connected to the opposite panel adjacent the free edges thereof, for normally retaining these edges in lapped relation to close the slit 5.

It is obvious that instead of using two pairs of elastic strips any suitable number of pairs or single strips can be used, also that the sequence of fastening said pairs of strips or single strips may conveniently be altered and that the distance from each other at which the pairs of strips or single strips are fastened may vary according to the special design or cut of the bedjacket or similar wearing apparel.

What I claim as my invention and desire to secure by Letters Patent of the United States is:

1. A closure for a bedjacket having a neck opening, opposed arm hole seams, and separable panels having adjacent free edges normally overlapped in symmetrical relation to a center line extending

from the bottom of the garment to a point adjacent the neck opening where the panels are connected; comprising a pair of strips of elastic material, the opposed ends of said strips being connected to the respective arm hole seams, the strips extending transversely across the respective panels and having their adjacent ends connected to respectively opposed panels at opposite sides of said line for yieldably maintaining said edges in normally overlapped relation.

2. The structure according to claim 1, together with a second pair of strips of elastic material in vertically spaced relation to the first pair of strips and having their opposed ends connected to the respective arm hole seams, and their adjacent ends connected to respectively opposed panels at opposite sides of said line.

3. A bedjacket or similar garment having a neck opening, opposed arm hole seams and separable back panels having adjacent free edges intermediate the arm holes and extending from the bottom of the garment to a point a short distance below the neck opening, and means for yieldably retaining the said edges in lapped garment closing position comprising two vertically spaced

5 pairs of elastic strips, one strip of each pair having one end thereof connected to an arm hole seam and extending across the adjacent panel and having its opposite end connected to the opposed panel adjacent its free edge and the other strip of each pair having one end thereof connected to the opposed arm hole seam and extending across the adjacent panel and having its opposite end connected to the opposed panel adjacent the free edge thereof.
